UNITED STATES PATENT OFFICE.

HENRY TRENCHARD, JR., OF BROOKLYN, NEW YORK.

STRING-CLOSURE-AFFIXING MACHINE.

1,258,829.

Specification of Letters Patent. Patented Mar. 12, 1918.

Application filed December 30, 1915. Serial No. 69,392.

To all whom it may concern:

Be it known that I, HENRY TRENCHARD, Jr., a citizen of the United States, and a resident of the city of New York, borough 5 of Brooklyn, county of Kings, and State of New York, have invented an Improvement in String - Closure - Affixing Machines, of which the following is a specification.

This invention relates generally to paper working machinery and more particularly to a machine for the manufacture of the so-called double button and string closure which has its most general application to merchandise envelopes and the like, these envelopes 10 being commonly termed double button envelopes. These envelopes are characterized by a button or washer of relatively unyielding paper stock fastened to the flap of the envelop and a similar button or washer fastened to the body of the envelop and a string which is attached to the flap or body of the envelop and is adapted to be passed under the buttons to effect a closure of the envelop.

The object of the invention is to provide 25 a means in such a machine for automatically accomplishing the several operations incident to the manufacture of this type of fastener.

For convenience in the description of the 30 particular embodiment of this invention, it may be noted that the construction generally adopted for these envelopes is to have upon the inside of the envelop body a comparatively light reinforcing washer and a 35 comparatively stiff fastening washer or button upon the outside and to have these washers united through a hole in the body of the envelop by means of an eyelet which is upset to engage the two washers and hold them 40 securely in position in relation to the body of the envelop. Upon the flap of the envelop a similar construction is usually employed except that a string, which is used to effect the closure of the envelop, has one end fastened 45 under the eyelet which attaches the coöperating washers to the flap of the envelop. We may for the present disregard the washers which are affixed to the body of the envelop, and confine our attention to the washers and 50 string which are affixed to the flap of the envelop, although it will, of course, be understood that the machine, later to be described, may be adapted for affixing the washers and string to the body of the envelop 55 instead of to the flap.

As these envelops have heretofore generally been made by hand with the aid of a pair of coöperating dies to upset the eyelet and semi-automatic means to feed the eyelets, it has been customary to place the reinforcing washer upon the male die and then to insert the end of the tying string through a hole which has been previously made in the flap of the envelop and to place the flap of the envelop with the string so held over 60 the male die. The string is then given a turn about the male die, the fastening washer is placed thereon and the eyelet feeding and eyelet setting mechanism operated to force an eyelet through the hole in the fastening 65 washer, the envelop flap, and the reinforcing washer, and to upset the eyelet on the inside of the flap and beneath the reinforcing washer.

The present invention provides means to 70 accomplish these operations in a substantially automatic manner.

One embodiment of the invention has been herein selected for purposes of illustration and explanation and is shown in the accompanying drawings, wherein—

Figure 1 is a diagrammatic elevation of a portion of a machine showing the mechanism embodying the invention;

Fig. 2 is a partly diagrammatic end elevation of the embodiment of the invention shown in Fig. 1;

Fig. 3 is a top plan view of a portion of the machine;

Fig. 4 is a longitudinal section on the line 90 4—4 of Fig. 2;

Figs. 5, 6 and 7 are details later to be referred to;

Fig. 8 is an end elevation particularly of the string cutting mechanism, showing the 95 same in operative position; and

Figs. 9 and 10, are detail views later to be referred to.

Figs. 11, 12 and 13 show an envelop provided with a string closure of the type hereinafter referred to.

Referring to Fig. 1 of the drawings which shows the machine in a somewhat diagrammatic form, a pair of coöperating dies 1 and 2 are adapted to be operated from a main shaft 3 by any suitable means or by any suitable mechanical movement to cause them, in this particular disclosure, to be brought together once for each revolution of the main shaft. Means may also be provided, but 110

which are not herein shown, to cause the dies as they approach each other to punch washers from strips of paper and to carry them forward to form the fastening washer 5 and reinforcing washer respectively for the envelop flap. Further means may be provided for automatically feeding an eyelet to the machine to position it upon a slideable pin 4 which is loosely mounted in a centrally 10 bored hole in the die 2 and is held, when uncontrolled, in the extended position herein shown by a spring 5. For the purposes of this application, the eyelet feeding and washer forming means may be disregarded 15 and our attention confined to the means for adding the string to the completed combination of washers, eyelet and envelop flap.

The attachment of the string to the flap of the envelop may be effected by looping 20 the string around the pin 4 before the dies have been brought together to upset the eyelet. It will readily be observed how this is effected when the reinforcing washer is placed upon the die 1, as shown in Fig. 4, 25 and the eyelet and fastening washer are placed upon the pin 4 mounted in the die 2 before the dies have been caused to approach each other. If the envelop flap be then inserted between the dies, and the dies be 30 caused to come together, the string which has been previously wound upon the pin, is caught between the envelop flap and the reinforcing washer and firmly held there by the flanges of the eyelet.

35 Means for accomplishing this result are herein shown as a hollow gear 6 mounted within a suitable housing and rotating concentrically about the pin 4 and of sufficient size to permit the die 2 to pass therethrough. 40 This gear is rotated from the main shaft 3 by a suitable train of gearing comprising the gears 7, 8 and 9 and is preferably rotated at a greater angular speed than the main shaft. In this instance the gear 6 which, with its 45 associated parts, will hereinafter be termed the "looper" makes four revolutions to one revolution of the main shaft. Means are provided on the gear to grasp the end of a string which is presented to the looper by means

50 hereinafter described, the string grasping means being herein shown as a substantially U-shaped member 10 normally spring pressed against the face of the gear, but adapted to be extended from the face of the 55 gear at the proper moment in the operation of the machine when it is desired to grasp a piece of string presented thereto. This U-shaped member 10 extends through the gear and is fixed to a ring 11 having a cam surface 12. The construction of this looper will be more readily seen from Figs. 5, 6 and 7 which are respectively an end view, front view and cross-section of the looper. The ring 11 is normally held away from the gear 60 by springs 13 and its movement is limited by

the string engaging member 10. Thus, it will be seen that when an end of a string is placed under the member 10, it will be firmly grasped between this member 10 and the face of the gear in the absence of any control 70 thereof by the ring 11 with its cam surface 12.

Means may be provided to control the opening and closing of the member 10 for the purpose of threading the string thereunder, 75 the said means being herein shown as a cam 14 mounted upon a lever 15 and controlled by a cam 16 upon the main shaft. As this particular mechanism is designed to operate, it is desirable to have the looper opened for 80 grasping the string once in its four revolutions, that is at a time when the pin 4 is extended and after the washers, eyelet and envelop flap have been placed in position. It will therefore be seen that when the cam 14 85 is brought to the position shown in Fig. 4, the looper, rotating in a counter-clockwise direction will be opened by the cam 14 for threading the string. As the looper continues to rotate the high point of the cam 90 surface 12 is rotated past the cam 14 and the string engaging member 10 will grasp the string end which has been presented to it and will wind the string about the pin 4 until the string is released or withdrawn from 95 the looper.

Means may be provided to present the end of a string to the looper mechanism so that it may be engaged by the member 10 and the rim of the gear 6, the same being herein 100 shown as a reciprocating string carrying member 17 and its associated parts. This string carrying member is provided with a finger 18 having a resilient side plate 19 to engage the string when it is threaded therethrough and to tension the string during the 105 succeeding operations. The string carrying member 17 is mounted in a guideway 20 and is reciprocated by a crank arm 21 and link 22, the crank arm being mounted upon a 110 shaft 23 which in this particular instance, is driven in synchronism with the main shaft 3 through a train of gears, 24, 25, 26, 27 and 28.

Means may be provided to sever the 115 string, the same being herein shown as shears 29 having a fixed blade 30 and movable blade 31 and mounted upon an oscillating member 32 pivoted at 33 upon the guideway. The two blades of the shears are pivoted at 34 and are held in operative relation by any suitable means herein shown as a stud and spring 33. Suitable means may be provided to bring the shears into position for cutting the string, the same being herein 120 shown as a cam 36 upon the oscillating shears mounting 32 adapted to be engaged by an anti-friction roller 37 upon the string carrying member 17 to oscillate the shears and bring them into operative position for 125 130

cutting the string. The shears mounting is shown in its normal position in Fig. 2 and is yieldingly held in this position by a spring 38 attached to the shears mounting 5 and to an arm 39 which in turn is rigidly attached to the guideway 20.

Means may be provided to operate the shears to cause them to cut the string upon their being brought forward through the 10 aperture 40 in the guideway, such means being herein shown as an anti-friction roller 41 upon the rearwardly extending movable blade 31 of the shears. This roller 41 is adapted to be engaged by a pair of cams 42 15 and 43 which cause the shears to close and open respectively. This particular means for effecting the closing and opening of the shears will be more clearly understood from Figs. 9 and 10 which are detail plan views 20 of the shears and the shears operating mechanism. It will be observed that when the shears mounting is oscillated upon the pivot 33 the shears will be swung forward until the anti-friction roller 41 contacts with the 25 cam 42. Upon further forward movement of the shears the cam 42 will operate to bring the cutting edges of the shears together and thereupon the machine being so organized as to bring the string between 30 these cutting edges, the string will be severed just above the threader. As the string carrying member is moved upward by the crank and link connection with the shaft 23 the roller 37 upon the string carrying member will be released from engagement with the cam 36 upon the shears mounting and allow the same to resume its normal position under the action of the spring 38. The rearward movement of the shears will bring 35 the shears operating roller 41 in contact with the cam 43 which will cause the shears to be opened in readiness for the next forward movement preceding the cutting of the next length of string.

40 In operating the particular mechanism disclosed, the light reinforcing washer may be placed upon the die 1 and the eyelet and fastening washer upon the pin 4. The operation of the main shaft 3 45 is controlled by some suitable clutch mechanism and, upon the insertion of the envelop flap in its proper position between the dies, the clutch may be released and the shaft 3 rotated to cause the string feeding means 50 to operate and the dies to come together. This operation may take place somewhat as follows, assuming that the parts at the start are in the position shown in Figs. 1, 2 and 4. The string end 44 will be presented by 55 the string threader 19 to the string engaging means 10 which is held in the position shown in Fig. 4 by the cam 14 controlled from the cam 16 upon the main shaft. Upon the rotation of the main shaft the 60 looper will be rotated and the high point 65

of the cam surface 12 will pass the cam 14, thus causing the string engaging member 10 to press against the side of the looper gear and grasp the string firmly. The cam 14 will then be withdrawn from its operative 70 position shown in Fig. 4 by the lever 15 under the tension of the spring 45 and will not thereafter affect the operation of the looper until raised by the cam 16 upon the main shaft at the completion of another 75 revolution of the main shaft.

The string having been engaged by the looper the parts are so related that the string carrier 17 will then descend in the guideway 20 and simultaneously the looper, 80 drawing the string through the string threader 18, will begin to wind the string around the pin 4. As previously noted the looper, in this particular apparatus, is arranged to make four revolutions to each single revolution of the main shaft 3. When the looper has nearly completed its second revolution and the string carrier 17 is approaching the lower end of the guideway, the dies 1 and 2 are brought together by any 85 suitable die operating means which may be operatively connected with the main shaft 3. This will cause the eyelet to be forced through the fastening washer and through the loop of string upon the pin 4. The eyelet will then pass through the envelop flap and the reinforcing washer carried by the die 1 and be upset by the die 1, thus firmly attaching the string and washer to the flap of the envelop. This upsetting of the eyelet is arranged to take place approximately 90 when the looper has completed its second revolution. When the eyelet has thus been upset and the string firmly fastened beneath its flanges the end of the string which was 95 held by the looper will be pulled out of engagement by the string engaging member 10.

100 Approximately at the time when the string is fastened under the eyelet or shortly thereafter the string carrier 17 will engage 110 the cam 36 upon the shears mounting and the shears will be swung out through the aperture 40 in the guideway into the path of the string. The string may at this time be held taut between the string threader 115 and the looper, and the shears upon the further descent of the string carrier to its lowermost point will operate to sever the string just above the string threader.

120 The foregoing is accomplished in approximately one-half a revolution of the main shaft. During the other half of the main shaft revolution the looper having completed the performance of its function revolves freely about the dies. The string carrier 17 is now moved upwardly in the guideway thus releasing the roller 37 from engagement with the cam 36 and causing the shears to swing back to their normal position as shown in Fig. 2. The string carrier 130

is then brought to its highest position and brings the string end in position to be engaged by the looper in the next cycle of operation of the machine. During the fourth revolution of the looper and as the main shaft is completing its single revolution, the cam 16 engages the lever 15 and causes the cam 14 to assume the position shown in Fig. 1. As the looper completes its fourth revolution the cam surface 12 engages the cam 14 and opens the string engaging member 10. Also toward the completion of the single revolution of the main shaft the dies are drawn apart and are positioned ready for the next cycle of operation of the machine. An eyelet and the washers may then be put in place and the operation repeated.

Figs. 11, 12 and 13 show an envelop provided with a string closure which may be affixed by the above described apparatus. The envelop body 50 is provided with a flap 51 adapted to be folded down as shown in Fig. 12. A fastening washer 52, and a reinforcing washer 53 are affixed to the front 25 of the body portion by an eyelet 54. A fastening washer 55 and a reinforcing washer 56 are affixed by an eyelet 57 to the flap of the envelop and the tying string 58 is held by the upset flange of the eyelet 57 between the flap 51 and washer 55. In Fig. 13 a fastening washer 55 is cut away and the eyelet 57 is shown in section transverse of its shank. This figure shows the manner in which the string 58 is wound about the eyelet to secure a very firm and permanent attachment therewith.

It will be seen from the foregoing description of this embodiment of the invention that the invention provides an efficient 40 automatic means for accomplishing certain of the operations incident to the manufacture of this general type of closure which has been herein described in its most general application as a closure for envelopes and the like. It is contemplated that this invention 45 may be modified to effect the manufacture of a similar closure as applied to other articles than envelopes and that the invention may be variously embodied within the scope 50 of the subjoined claims.

I claim as my invention:

1. In a machine of the character described, the combination of eyelet setting means and automatic means to loop a string 55 in position to be fastened between the upset flanges of an eyelet.

2. In a machine of the character described, the combination of eyelet setting means, automatic means to loop a string in 60 position to be fastened between the upset flanges of an eyelet, and means to sever a predetermined length of string.

3. In a machine of the character described, the combination of eyelet setting 65 means, means to form a loop of string for

engagement by the eyelet, and means to present a free end of string to the said string looping means.

4. In a machine of the character described, the combination of eyelet setting 70 means, means to form a loop of string for engagement by the eyelet, means to present a free end of string to the said string looping means and means to sever a predetermined length of string. 75

5. In a machine of the character described, the combination of eyelet setting means and means to position a string to be fastened between the upset flanges of an eyelet, the said last named means comprising a 80 rotatable string engaging member adjacent to said eyelet setting means.

6. In a machine of the character described, the combination of eyelet setting 85 means, means to position a string to be fastened between the upset flanges of an eyelet, the said means comprising a rotatable string engaging member adjacent to said eyelet setting means, and further means to present a free end of string to said string engaging 90 member.

7. In a machine of the character described, the combination of eyelet setting means, means to position a string to be fastened between the upset flanges of an eyelet 95 comprising a rotatable string engaging member adjacent to said eyelet setting means, means to present a free end of a string to said string engaging member, and means to sever a predetermined length of 100 string.

8. In a machine of the character described, the combination of eyelet setting means having a yieldingly mounted pin and automatic string looping means to loop a 105 string about the pin.

9. In a machine of the character described, the combination of eyelet setting means having a yieldingly mounted pin and automatic string looping means to loop a 110 string about the pin comprising cam controlled string engaging means.

10. In a machine of the character described, the combination of eyelet setting means having a spring pressed pin and automatic string looping means to loop a string about the pin comprising string engaging means operating concentrically about said pin. 115

11. In a machine of the character described, the combination of eyelet setting means having a spring pressed pin and automatic string looping means to loop a string about the pin comprising cam controlled string engaging means operating concentrically about said pin. 120

12. In a machine of the character described, the combination of eyelet setting means, automatic means to position a free end of string for fastening beneath the upset 125

flanges of an eyelet to be set by said first named means comprising string looping means, string presenting means, and means to sever a predetermined length of string.

5 13. In a machine of the character described, a string presenting means including a reciprocatable string presenting member, and a guideway therefor, string cutting means adapted to be interposed in the path 10 of the string and operable by the reciprocation of the string carrying member.

14. In a machine of the character described, a string presenting means including a reciprocatable string carrying member, and 15 a guideway therefor, string cutting means comprising shears mounted to swing into the path of the string and a cam upon said shears mounting engageable by the string carrying member to bring the shears into 20 operative position.

15. In a machine of the character described, a string presenting means including

a reciprocatable string carrying member and a guideway therefor, string cutting means comprising shears mounted to swing into the 25 path of the string, a cam upon said shears mounting engageable by the string carrying member to bring the shears into operative position and shears operating means.

16. In a machine of the character described, a string presenting means including a reciprocatable string carrying member, and a guideway therefor, string cutting means comprising shears mounted to swing into the path of the string, a cam upon said shears 35 mounting engageable by the string carrying member to bring the shears into operative position and cams to open and close the shears.

In testimony whereof, I have signed my 40 name to this specification this twenty-fourth day of December, 1915.

HENRY TRENCHARD, JR.
